Primary Examiner — Paula Greene*(74) Attorney, Agent, or Firm* — Muncy, Geissler, Olds & Lowe, P.C.(57) **CLAIM**

The ornamental design for a loupe, as shown and described.

DESCRIPTION

FIG. 1 is a front view of a loupe in a full extension posture showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front view of the loupe in a folded posture;

FIG. 8 is a rear view thereof;

FIG. 9 is a top view thereof;

FIG. 10 is a bottom view thereof;

FIG. 11 is a right side view thereof;

FIG. 12 is a left side view thereof;

FIG. 13 is a perspective view of the loupe in a stand up posture in which the loupe is able to stand by itself; and,

FIG. 14 is an alternate perspective view of the loupe in a posture by which the user handily holds and uses the loupe with one hand.

The broken lines and the areas within the broken lines are included for illustrative purposes only and form no part of the claimed design.
